UNITED STATES PATENT OFFICE.

WILLIAM G. METZGER AND HENRIETTA V. METZGER, OF CLEVELAND, OHIO.

MATTRESS-COVER.

1,250,201.

Specification of Letters Patent. Patented Dec. 18, 1917.

Application filed February 1, 1915. Serial No. 5,353.

To all whom it may concern:

Be it known that we, WILLIAM G. METZGER and HENRIETTA V. METZGER, citizens of the United States, residing at Cleveland, in the 5 county of Cuyahoga and State of Ohio, have invented a certain new and useful Improvement in Mattress-Covers, of which the following is a full, clear, and exact description, reference being had to the accompanying 10 drawings.

This invention relates to that class of devices known as mattress covers, that are used for inclosing or covering mattresses for the purpose of protecting them from soil and 15 wear.

The object of the invention is to provide a device of the above character that will completely inclose and thoroughly protect the mattress; that may be very conveniently 20 opened to entirely expose the mattress, when it is desired to turn the latter; that may be secured to some part of the bed structure, such as the bed spring, thereby to hold the cover, and also the mattress, in correct 25 position with respect to the spring; that may be folded to facilitate handling; that may be very easily washed or cleaned, and that has incorporated within it, means for imparting a proper shape to the cover.

To these ends, the invention provides a 30 mattress cover comprising, generally, a sheet of suitable fabric that is of substantially the size and shape of a mattress and having its edges provided with tubing for the reception 35 of frame members which, when properly assembled, impart to the aforesaid sheet its correct shape; and from the edges of the sheet there extend flaps that are adapted to be folded up and over the top of the mattress 40 to completely inclose the same.

A further and more limited object comprehended by our invention is the provision of a so called "knock down" frame that is made up of separable members that may be easily 45 inserted into or removed from the tubing of the cover; to provide joints within the frame whereby the same may be folded, while within the cover, to facilitate the handling; to provide flaps for the openings through which 50 the frame members are inserted into the tub-

ing; and, in certain embodiments of our invention, to provide a common means for holding the frame members together and for securing the mattress cover to the bed spring.

In the accompanying drawing there is 55 shown a mattress cover wherein the foregoing objects are attained, and while we will proceed to describe the same in detail, we wish to be understood as not limiting ourselves to the structural details thereof fur- 60 ther than is required by the terms of the annexed claims and is rendered necessary by the state of the prior art.

In the drawings, Figure 1 is a perspective view of our mattress cover partially inclos- 65 ing a mattress, parts being broken away to reveal the hinge joint of one of the frame members; Fig. 2 is a transverse section through a mattress and cover that are supported by a bed spring, the view being of a 70 more or less conventional nature; Fig. 3 is a perspective view of a corner of the mattress cover as viewed from the inside; Fig. 4 is a similar view of a fragment of the frame; and Fig. 5 is a sectional detail showing a 75 modified form of the securing means for attaching the ends of the frame members.

The mattress cover is preferably made of some such durable material as heavy duck or canvas, and a rectangular sheet of such 80 material, of a shape and size corresponding to the mattress to which the cover is to be fitted, constitutes the bottom 1 of the cover. The edges of the bottom are provided with tubes 2 that may be formed by turning 85 each edge of the bottom upward and over on itself and stitching the edge to the body portion of the bottom, as shown at 3. From one of the lateral edges of the bottom there extends a flap 4 that is preferably of a width 90 sufficient to extend up the side of the mattress and across the top thereof to about its center. A flap 5 is secured to the opposite edge of the bottom 1 and is here shown as wide enough to extend up the adjacent side 95 and across the top of the mattress and down the opposite side thereof, where its free edge, which is provided with the button holes 6, may be secured to the buttons 7 that are attached to the flap 4. While I have shown 100

buttons and button holes as the means for securing the free edge of the flap 5 to a part of the cover, any other suitable means, such as hooks and eyes or snap fasteners, may be 5 employed in their stead; or the flap 5 may be made ample enough to allow a portion of it to be tucked under the cover, thereby making it unnecessary to employ fastening means of any sort.

10 To each end of the bottom 1 there is attached a flap 10 which extends up and over the adjacent end of the mattress, as shown in Fig. 1. In folding the cover over the mattress, these may be the first to be folded 15 into place, the flap 4 being next spread over the flaps 10, and the flap 5 being then drawn over the top of the mattress and secured to, or tucked under the side of the cover to which the flap 4 is attached. For convenience, we prefer not to connect the adjacent edges of adjoining flaps where they meet at the corners of the mattress, although, if found desirable, such edges may be stitched or otherwise secured together to more effectively close the corners of the cover and prevent any possible admission of dust. 20 Where the ends of the side and end tubes 2 meet, they are cut away on their upper sides, preferably diagonally, as shown in Fig. 3, 25 and triangular flaps 11 are stitched to the tubes and are arranged to be folded down over the openings 12, through which the members of the "knock down" frame, previously referred to and next to be described, 30 may be inserted into the tubes.

The frame comprises side and end members 14 and 15, respectively, and each of the former is made jointed at about its middle for a reason already explained. A hinge 40 joint between the sections of each side member is conveniently made by bifurcating the opposed ends of the sections and fitting into the bifurcations thereof the opposite ends of a metal plate 16. The plate is pivoted 45 to each section upon a pin 17 that extends through said member and through a suitable perforation in the plate. This forms an inexpensive and very satisfactory means of hinging the two sections of each side member together, for it allows them to be turned one upon the other, and at the same time prevents any appreciable lateral divergence 50 of the sections.

The overlying ends of joined members are 55 shown herein as complementarily rabbeted, and in the preferred embodiment, the ends are held together by a bolt 20 which extends down through alining apertures in the two members, and passes through a hole in the bottom 1 of the mattress cover. A clamping plate 21 is carried by each of the bolts 20, and is retained upon the bolts by a wing nut 22. When the mattress cover is in use, the bolts 20 are intended to pass down between wires or other parts of the bed spring, 60

and the plate 21 clamped tightly against such portion of the spring, as indicated in Fig. 2, wherein the spring is represented conventionally at 23.

From the foregoing description it will be 70 seen that when it is desired to disassemble the frame and remove the members thereof from the tubes of the cover, the same may be very easily accomplished by turning back the flaps 11 and removing the bolts 20, when 75 the members of the frame can be very easily withdrawn from their respective tubes.

When some other means than the bolts 20 is used for securing the mattress cover to the bed spring, or to some other part of the 80 bed, or when such fastening means is dispensed with entirely, the ends of the frame members may be very neatly connected by means of the screw 24, shown in Fig. 5. The screw has a tapered head that can be countersunk in one of the frame members, and the screw threaded into a thimble 25 that is permanently embedded in the other member of the frame. 85

Having thus described our invention, what 90 we claim is:—

1. A mattress cover comprising an envelop for the mattress, a rectangular "knock-down" frame to which the sides and ends of the envelop are secured, and common means 95 for connecting the adjacent ends of adjoining frame members together and for securing the frame to an adjoining structure.

2. A mattress cover comprising a substantially rectangular sheet, a tube extending along each edge of the sheet, a flap attached to each edge of the sheet and arranged to be folded up and over a mattress, a frame comprising members that are adapted to occupy the aforesaid tubes, and means 105 for connecting the adjacent ends of adjoining frame members, certain members of the frame being jointed.

3. A mattress cover comprising a substantially rectangular sheet, a tube extending 110 along each edge of the sheet, a flap attached to each edge of the sheet and arranged to be folded up and over a mattress, a frame comprising members that are adapted to occupy the aforesaid tubes, the adjacent ends 115 of adjoining frame members overlapping each other, bolts which are adapted to pass through the overlapping ends of said members, and means for application to the lower ends of the bolts for securing the frame to 120 an adjoining structure.

4. A mattress cover comprising a substantially rectangular sheet, a tube extending along each edge of the sheet, a flap attached 125 to each edge of the sheet and arranged to be folded up and over a mattress, a frame comprising members that are adapted to occupy the aforesaid tubes, the adjacent ends of adjoining frame members being rabbeted and overlying each other and being pro- 130

vided with vertically alining apertures, bolts which extend downward through the apertures and through the adjacent portion of the aforesaid sheet, clamping plates for application to the bolts, and nuts threaded upon the bolts for coöperation with said plates.

In testimony whereof, we hereunto affix

our signatures in the presence of two witnesses.
